FLEXIBLE SLEEVE FOR RUBBING MACHINES

Stephen A. Crosby, Chicago, Ill., assignor to Sterling Tool Products Company, a corporation of Illinois

Application October 18, 1944, Serial No. 559,176

4 Claims. (Cl. 51—170)

This invention relates to flexible sleeves adapted to connect movable parts and prevent oil and dirt from passing through the connection. The invention relates more particularly to an improved flexible sleeve adapted for use on rubbing or abrading machines where one of the parts moves at a high rate of speed with respect to the other.

The primary object of the invention is to provide an improved sleeve which will not wrinkle excessively and will have a long working life. The improved flexible sleeve is particularly adapted for use in a rubbing machine of the type shown in my application Serial No. 504,855, filed October 4, 1943, for a rubbing machine.

The invention is illustrated in a preferred embodiment in the accompanying drawing in which—

Figure 1 is a fragmentary elevational view of the lower portion of a rubbing machine on which the improved flexible sleeve has been installed; Fig. 2, a vertical sectional view taken as indicated at line 2—2 of Fig. 1; and Fig. 3, a perspective view of the sleeve.

In the embodiment illustrated, a rubbing machine has a supporting frame 4 on which is mounted in spaced relation for orbital movement a driving head 5, to which may be secured a rubbing pad 6. A counterpoise 7 is mounted between the driving head and supporting frame, to be driven in out of phase relation with respect to the driving head, so as to balance out vibration forces when the machine is operated at high speed.

In the embodiment illustrated, the lower portion of the supporting frame and the driving head are substantially rectangular in plan, and the driving head has a perimetral dove-tail edge 8, to which the lower portion of the flexible sleeve 9 may be attached. The supporting frame is shown with an outwardly extending flange 10, over which the upper edge of the flexible sleeve may be snapped, and preferably the frame has a downwardly extending hood 11, which will enclose the upper portion of the flexible sleeve. As best shown in Figs. 2 and 3, the flexible sleeve 9 has a molded perimetral slot 12, which fits tightly over the flange 8 on the driving head and may be cemented thereto. Its top portion has an outwardly extending flange 13, which serves to close the space between the supporting frame 4 and the hood 11.

When the driving head makes its orbital movement with respect to the supporting frame, the closure sleeve which preferably is made of rubber, synthetic or natural, must accommodate it-

self to the movement. It has been found that this action normally wrinkles the sleeve, and may cause the central portion of the sleeve to rub against the bottom edge of the hood 11. Most of this wrinkling effect is eliminated by the present construction, wherein a longitudinally extending rib 14 is molded on the inner face of the sleeve, so as to be coextensive with the two longer sides of the rectangle. These integrally formed ribs have been found to greatly lengthen the life of the sleeve, and enable the lateral portions of the counterpoise to be sealed in, so that dust and dirt will not enter between the parts, and oil will not leak out.

15 The foregoing detailed description is given for clearness of understanding only, and no unnecessary limitations should be understood therefrom, for some modifications will be obvious to those skilled in the art.

20 I claim:

1. In a rubbing machine having a supporting frame and a drive head mounted for movement with respect to the frame, a flexible closure between said head and frame comprising: a 25 perimetral sleeve of rubber-like material having a head portion adapted to grip tightly the lower portion of the supporting frame and a base portion to grip the marginal edge portion of the drive head, said sleeve having a longitudinally extending rib near the central portion of the sleeve to reduce wrinkling when the head is moved with respect to the frame.

2. A flexible closure sleeve as specified in claim 1, in which its base portion is shaped to 35 make a dove-tail connection with the marginal edge portion of the drive head, said dove-tail connection to extend completely around the drive head.

3. In a rubbing machine: a supporting frame, 40 a drive head mounted for orbital movement with respect to said frame, a counterpoise disposed between said frame and drive head, means on the frame for driving said counterpoise and drive head in out of phase relation, and a flexible 45 sleeve forming a lateral closure for the counterpoise and making a liquid tight connection with marginal portions of the driving head and lower portion of the frame, said sleeve having an integrally formed longitudinal rib on its inner face 50 near its central portion to reduce wrinkling.

4. Apparatus as specified in claim 3, in which the supporting frame and drive head are substantially rectangular in plan and the rib extends inwardly from each of the longer sides of the rectangular sleeve.

STEPHEN A. CROSBY.
